UNITED STATES PATENT OFFICE

EDWARD A. ANDERSON, OF CHICAGO, ILLINOIS, ASSIGNOR TO THE AUTOMATIC RECORDING SAFE COMPANY, OF CHICAGO, ILLINOIS, A CORPORATION OF ILLINOIS

SAVINGS BANK

Application filed January 16, 1930. Serial No. 421,168.

This invention relates particularly to savings banks of the book form type; and the primary object is to provide an extremely simple and durable construction which can be cheaply manufactured.

The invention is illustrated in a preferred embodiment in the accompanying drawing, in which—

Figure 1 is a perspective view of a savings bank embodying the invention; Fig. 2, a sectional view on an enlarged scale, taken as indicated at line 2—2 of Fig. 1; Fig. 3, a transverse section taken as indicated by the line 3 of Fig. 2; Fig. 4, a perspective view 15 of the main body of the casing before the pads and cover fabric have been applied; and Fig. 5, a broken perspective view of the U-shape closure employed.

In the illustration given, the savings bank 20 comprises a main casing section A and a U-shape closure B.

The casing A comprises a sheet metal member 1 which is bent into U-form, thus providing side walls 1^a and a back 1^b; cardboard 25 filler-sheets 2 lying in depressions 1^c which are formed by striking the main portions of the side walls of the member 1 inwardly; padding sheets 3, which may consist of loosely felted soft fibrous material, placed upon 30 the outer sides of the casing; and a cover fabric 4 which completes the binding applied to the U-shape sheet metal member 1, to complete the simulation of the sides and back of the book. Suitable legends or titles 35 (not shown) may be printed upon the binding.

Somewhat stiff paper sheets 3^a are interposed between the padding sheets 3 and the cover fabric 4, facilitating the application of 40 the covering, that is, preventing disarrangement of the material 3 while the cover is being applied. The sheets 3^a preferably are secured to the outer surfaces of the loosely felted sheets 3 by means of an adhesive; and 45 the composite sheets are then laid within the space bounded by the marginal flange 1^d which is formed by bending the edges of the sheet metal outwardly and then inwardly over the adjacent portions of the sheet metal.

The marginal portions of the fabric 4 are

indicated at 4^a. These marginal portions are folded inwardly over the edges of the sheet metal and pasted to the inner marginal portions of the sheet metal.

The side walls 1^a are connected by short 55 posts 5. These posts preferably are of U-shape cross-section, as shown in Fig. 2, and are set between the depressed portions 1^c of the side walls. The extremities of the posts are provided with 60 lugs 5^a which extend through the sheet metal and are clenched upon the outer surfaces of the depressed portions, as shown in Fig. 4. Two of the posts are shown provided with slots 5^b which are adapted to be engaged by 65 the locking device with which the closure B is equipped.

The closure B is shown as consisting of a U-shape brass member which is of U-shape cross-section, the member thus affording a 70 peripheral closure wall 6 and inturned flanges 6^a. The outer surface of the closure is given a silk finish to simulate the gilded edges of leaves. The extremities of the arms of the closure are provided with slots 6^b which engage lugs 1^e with which the back wall 1^b is equipped near its ends. The lugs 1^e are formed by providing the back wall with extensions which are bent inwardly against the inner surface of the back wall and then forwardly, as will be clearly understood from 75 Fig. 2.

The closure is shown equipped at one end with a coin slot 7 and a suitable slot-guard 85 device 7^a. The longitudinal portion of the closure B is equipped with a sliding bolt 8 controlled by a lock 9. The bolt 8 is normally held in the locked position by means of a spring 9^a. The extremities of the bolt are 90 equipped with lugs 8^a which engage the slots 5^b. It will be noted that the locking bolt is slidably housed within the longitudinal portion of the channel member which forms the closure.

By reference to Fig. 4, it will be understood that when the metal is struck in to form the depressions 1^c in the side walls of the main casing, there are formed internal shoulders 1^f. These shoulders afford guides or abut- 100

ments with which the flanges of the closure B contact. It will be noted that the end shoulders 1^t serve as guides for the arms of the closure when the closure is being applied, and that the flanges of the longitudinal portion of the closure engage the longitudinal shoulders 1^t in the manner shown in Fig. 2.

The formation of the main portion of the casing in the manner described enables a comparatively light sheet metal plate to be employed in forming a casing of great strength and rigidity. Also, the manner of formation provides the internal shoulders 1^t and at the same time provides external depressions which enable the padding to be applied in a very satisfactory manner.

The closure B may be unlocked and withdrawn by means of a suitable key, when desired.

20 The foregoing detailed description has been given for clearness of understanding only, and no unnecessary limitations should be understood therefrom.

25 What I regard as new, and desire to secure by Letters Patent, is:

1. A savings bank having a casing section of U-form cross-section with edge portions of sheet metal which are turned outwardly and then backwardly upon adjacent portions 30 of the metal to form flanges; padding sheets applied to the side walls of said casing section between said flanges; and a fabric covering for said casing section, folded inwardly about the edge portions and joined to the inner surfaces of said side walls.

2. A savings-bank comprising a main sheet-metal casing-section of U-form cross-section having the main portions of the side-walls struck inwardly, thus providing external filler-receiving depressions and internal guide-shoulders; posts connecting the side walls of said casing at the inwardly struck portions; filler-sheets in said depressions; a flexible cover applied to said casing-section; and a U-shape closure having flanges engaging said shoulders.

EDWARD A. ANDERSON.
